UNITED STATES PATENT OFFICE.

JASPER L. ACKERMAN, OF MONTICELLO, INDIANA, ASSIGNOR OF FORTY-NINE PER CENT TO JLAC MANUFACTURING COMPANY, OF MONTICELLO, INDIANA, A CO-PARTNERSHIP OF JASPER L. ACKERMAN, IRA HAMIL, SAMUEL W. THOMPSON, LAWRENCE D. CAREY, AND BERNARD A. VOGEL.

GOLF-BAG ATTACHMENT.

Application filed April 28, 1923. Serial No. 635,235.

To all whom it may concern:

Be it known that I, JASPER L. ACKERMAN, a citizen of the United States, and a resident of Monticello, county of White, and State 5 of Indiana, have invented a certain new and useful Golf-Bag Attachment; and I do hereby declare that the following is a full, clear, and exact description thereof, reference being had to the accompanying drawings, in 10 which like numerals refer to like parts.

This invention relates to an attachment for a golf bag, and particularly to a combination support and counter therefor.

The object of the invention is to provide 15 an attachment which may be readily mounted upon the exterior of the golf bag which will enable the user thereof to anchor the bag in the ground so that it will stand upright when he wishes to take a stroke, rather 20 than dropping the bag upon the ground.

A second object of the invention is to provide in conjunction with the anchoring means, an automatic counter which will register 25 a count each time the anchoring means is actuated by resting the bag to make a stroke. This will enable the player to accurately keep track of the number of the strokes taken from the tee to the putting green, provided that the bag is not anchored 30 for other purposes, such as in hunting a ball.

One feature of the invention resides in the anchoring means comprising a longitudinal- 35 ly extending pin having supporting guides therefor secured to the bag, and means for forcing the pin downwardly into the ground for anchoring the bag thereto and holding it in upright position, and the yielding means for aiding in the release of the pin or 40 anchor from the ground and normally maintaining it above the bottom of the bag.

Another feature of the invention comprises an automatic counter associated with and connected to the anchoring pin so that 45 every time it is operated, the counter will be actuated and register successive numbers for indicating the number of times that the bag has been anchored in upright position. This arrangement will aid the player in 50 counting the number of strokes assuming that he will so position his bag each time he stops to take a stroke. Of course, the player would have to make allowances for

such times he anchored the bag for other purposes or took more than one stroke while 55 the bag remains in the same position as upon the putting green.

The full nature of the invention will be understood from the accompanying drawings and the following description and 60 claims.

In the drawings Fig. 1 is a perspective view of a golf bag showing the attachment mounted thereon. Fig. 2 is a side elevation showing an enlarged view of the attachment with portions thereof broken away and shown in cross section. Fig. 3 is a section taken on the line 3—3 of Fig. 1. Fig. 4 is an enlarged front elevation of the 65 actuating mechanism.

In the drawings there is shown a golf bag 10 of the usual type having a ball pocket 11, shoulder strap 12 and handle 13. The bag is provided with rigid vertical bracing strips 14, a bottom protecting cap 15, and a top 70 leather protecting and stiffening band 16.

Rigidly secured by rivets or other suitable means upon the bottom of the bag, there is a bracket 17 having a pair of openings through which the anchor pin or rod 18 is 80 adapted to slide and be vertically guided. The pin 18 continues upwardly into a cylindrical spring housing 19 which is rigidly secured at its upper end by the clamp 20 attached to the band 16. Within the cylindrical housing 19, there is a yielding spiral spring 21 which engages the bottom end 22 of the housing at one end and a nut 23 secured to the upper end of the pin 18. Between the nut 23 and the top of the housing 90 19, there is a pad 24. The spring 21 normally tends to maintain the pin in its upper position but permits it to be forced to anchoring position. Surrounding the pin 18 just above the middle of the bag, there is a 95 grasping handle 25 which enables the user to grasp the pin and force it into the ground upon placing his bag upright at rest. That portion of the pin extending into the ground will tend to anchor the bag and maintain it 100 in upright position, since it needs very little assistance for that purpose.

Clamped upon the cylindrical housing 19, there is a counter comprising an annular housing 26 having a face 27 provided with 105 the digits 28 from zero to 9. Contained

within the housing 26, there is a ratchet wheel 29 having a ratchet corresponding to each digit enumerated thereon, mounted upon a shaft supported by the housing and 5 having a pointer 30, one end thereof extending radially on the outside of the face and positioned to point to one of the digits. Slidably mounted upon the pin 18, there is a finger 31 having the end thereof formed to 10 engage the ratchet wheel 29 in such manner as to cause said wheel to make a single rotary movement upon each downward stroke given to the finger.

In operation, the finger 31 is adapted to 15 slide vertically in a bearing through the housing 26 and extend about the pin 18 upon which it is slidable. Upon the spring 21 elevating the pin 18 to its highest position, the handle 25 is brought into contact with 20 the finger 31 causing it to be elevated to such position as to enable it to engage another ratchet tooth. Upon forcing the pin 18 into the ground the handle releases the finger 31, and the spring 32, which is secured to 25 the housing 26, engages said pin, forcing it down so as to cause the ratchet wheel to turn. There is also provided a pawl 33 which is pivotally mounted on the housing 26 in such manner as to engage the ratchet teeth and 30 prevent the ratchet wheel from turning backward during the upward movement of the finger.

Upon securing this attachment to the bag, the player having turned the pointer 30 to 35 zero, upon approaching a tee, stands the bag up on the ground, and grasping the handle 25 forces the pin 18 downwardly, whereby the bag will be anchored. The finger 31 will rotate the ratchet wheel 29 so as to 40 bring the pointer 30 to the digit "1." He will then make his drive and one stroke will have been made and indicated on the counter. When he reaches his ball and prepares 45 to make the second stroke, he will again stand the bag up and anchor it, bringing the pointer 30 to the digit "2," indicating that he is about to make, or has made, a second stroke. This will be continued until he reaches the green, at which time the counter 50 will indicate the number of strokes he has taken up to that time. Naturally if he has so set his bag without taking a stroke, he must allow for that, although in practice the player would lay his bag on the ground without operating the counter in event he is hunting for a lost ball, or for any other purpose.

The invention claimed is:

1. An attachment for a golf bag comprising a cylinder having a closed top secured to the exterior of the bag, a bracket secured to the bottom of the bag on the exterior thereof, an anchor pin mounted on the exte-

rior of said bag having a pointed end slidably supported in said bracket and the upper end thereof extending into said cylinder, a 65 head on the upper end of said pin positioned within said cylinder, a cushion member mounted in said cylinder between said cylinder and the head thereof, a bearing plug secured on the lower open end of said cylinder for closing the same and providing a bearing for said pin, and a spring surrounding said pin and positioned between said plug and head for normally maintaining the head of said pin against said cushion. 75

2. An attachment for a golf bag comprising a cylinder having a closed top secured to the exterior of the bag, a bracket secured to the bottom of the bag on the exterior thereof, an anchor pin mounted on the exterior 80 of said bag having a pointed end slidably supported in said bracket and the upper end thereof extending into said cylinder, a head on the upper end of said pin positioned within said cylinder, a cushion member mounted 85 in said cylinder between said cylinder and the head thereof, a bearing plug secured on the lower open end of said cylinder for closing the same and providing a bearing for said pin, a spring surrounding said pin and positioned between said plug and head for normally maintaining the head of said pin against said cushion, and a handle mounted on said pin below said cylinder for permitting the same to be grasped and actuated for 90 anchoring purposes.

3. An attachment for a golf bag comprising a cylinder having a closed top secured to the exterior of the bag, a bracket secured to the bottom of the bag on the exterior 100 thereof, an anchor pin mounted on the exterior of said bag having a pointed end slidably supported in said bracket and the upper end thereof extending into said cylinder, a head on the upper end of said pin positioned within said cylinder, a cushion member mounted in said cylinder between said cylinder and the head thereof, a bearing plug secured on the lower open end of said cylinder for closing the same and providing 105 a bearing for said pin, a spring surrounding said pin and positioned between said plug and head for normally maintaining the head of said pin against said cushion, a counter having a ratchet member secured to said cylinder, and an actuating finger mounted on 110 said rod below said cylinder in position to engage with said ratchet and actuate said counter upon said pin being reciprocated in said cylinder. 115

In witness whereof, I have hereunto affixed my signature.

JASPER L. ACKERMAN.
